(57) **CLAIM**

The ornamental design for a shower head, as shown and described.

DESCRIPTION

FIG. 1 is a front view of a shower head embodying the design of the present invention;

FIG. 2 is a side view of the shower head illustrated in FIG. 1; FIG. 3 is a bottom view of the shower head illustrated in FIG. 1; and,

FIG. 4 is a rear view of the shower head illustrated in FIG. 1. The broken line showing is included for the purpose of illustrating and forms no part of the claimed design.
